(57) **CLAIM**

The ornamental design for a “SET OF STACKABLE CHESS PIECES” as shown and described.

DESCRIPTION

FIG. 1 is a top, front perspective view of a SET OF STACKABLE CHESS PIECES showing my new design, comprising, from left to right, a king piece, a queen piece, a bishop piece, a knight piece, a rook piece and a pawn piece;

FIG. 2 is a bottom, rear perspective view thereof;

FIG. 3 is front elevation view thereof;

FIG. 4 is a rear elevation view thereof;

FIG. 5 is a right-side elevation view thereof;

FIG. 6 is a left side elevation view thereof;

FIG. 7 is a top plan view thereof;

FIG. 8 is a bottom plan view thereof;

FIG. 9 is a perspective view of elements of the claimed design shown in an alternate position, and

FIG. 10 is a second perspective view of differing elements of the claimed design shown in an alternate position.

The broken lines in the drawings illustrate portions of the set of stackable chess pieces that form no part of the claimed design.
